UNITED STATES PATENT OFFICE

JOSEPH ZUBATY, OF FLINT, MICHIGAN, ASSIGNOR TO A C SPARK PLUG COMPANY, OF FLINT, MICHIGAN, A COMPANY OF MICHIGAN

SPEEDOMETER-MAGNET MOUNTING

Application filed June 8, 1928. Serial No. 283,995.

This invention relates to magnetic measuring instruments and while useful elsewhere, has been designed especially for use in connection with a combined speedometer 5 and odometer as used on motor vehicles.

An object of the invention is to provide means to secure the magnet in position on its support. Other objects such as simplicity in the holding means, economy and convenience in assembly will be appreciated from a reading of the following description.

In the drawing accompanying this description:

15 Figure 1 is a side elevation of a frame member of a magnetic speedometer having the improved magnet holding means incorporated therewith.

Figure 2 is a top plan view partly in section.

Referring by reference characters to the drawing, numeral 13 represents the frame of a combined speedometer and odometer. This frame is to be enclosed in a casing, the 25 latter to be secured to the instrument board of a motor vehicle, as usual. At 5 is shown a part of the conventional flexible drive shaft which is to make driving connection between a driving member, preferably one of the 30 driven shafts of the vehicle transmission, and the rotor shaft of the instrument. This rotor shaft will, as usual, be geared to the odometer wheels and also serves to rotate the rotor element within a fixed magnet and a 35 speed indicating cup. The invention is in no way concerned with the details of the odometer. It may be mentioned that clips 7 secure the shafts of the season and trip sets of number wheels, and also the shafts of 40 the star wheels associated therewith. At 17 is a shaft driven by the rotor shaft, an extreme lower end of which appears in Figure 1, and which is represented by numeral 19. At 21 is a clip holding the rotor shaft in position. 23 is a clip which holds shaft 17 in position.

The invention is, furthermore, not concerned with the details of a speedometer except for the provision for holding the magnet in position. There may be mentioned,

however, a top plate 27 secured by fastening means 25 to the frame. This top plate preferably is formed with an integral stop 31 to limit the rotation of the speed cup 33 under the influence of spring 35. This stop 55 engages lug 37 on the speed cup. The top plate is also provided with a part 39 for retaining the speed cup spindle from axial movement. The plate 27 also supports a bearing carrier 41 which supports the upper 60 hole jewel for the speed cup spindle in a well-known manner. The lower bearings for the speed cup spindle are not illustrated but may, in a well-known manner, be carried by the upper end of the rotor shaft. At 43 is a hair 65 spring adjuster rotatably supported on plate 27, preferably by the member 41 carried by the plate 27.

The invention constituting the subject matter of this application relates more particularly to the means for securing the horseshoe or U-shaped magnet in horizontal position on the frame 13. This frame is formed with angularly related vertical faces 51 and 53, as best shown in Figure 2 at the base of 70 which is a flat horizontal face 55, as shown in Figure 1. Upon this horizontal face the magnet rests its walls engaging the faces 51 and 53 in a manner which will be obvious upon inspection of the figures. A strap 9 75 of non-magnetic material is used to completely surround the U-shaped magnet 12 and secure it to the frame 13. From the frame 13 project two grooved studs 14, one for engagement with each end of the strap. 80 The strap has suitable terminal openings to receive the studs 14.

The strap is formed with crimps as at 15. When the magnet is to be placed on the frame, the strap may be hooked at one end over one 85 of the studs and then positioned to embrace the magnet, and the other end hooked over the other stud. Any looseness or slackness in the strap surrounding the magnet may be taken up by pinching either or both of the 90 crimped parts 15 so as to properly draw up the magnet tightly into position with its end faces in firm engagement with the several 95 faces of the frame which are to co-operate therewith in positioning the magnet. Such 100

a magnet mounting is extremely simple and cheap to manufacture. It is easy and quick in assembly and very effective in use.

If it be desired to secure a temperature compensating means, such a device may readily be clamped in position between the strap and the magnet.

I claim:

1. In combination with a measuring instrument including a frame and a fixed magnet, a strip terminally secured to said frame lying in the plane of and embracing said magnet, said frame having parts engaging said magnet, said strap having crimps to be 10 pinched to firmly secure said magnet in engagement with said frame parts.
2. In combination with a measuring instrument including a frame and a U-shaped magnet, said frame having angularly disposed faces engaging corresponding faces at 20 the ends of the legs of said magnet, a strap in the plane of the magnet having openings in its ends and intermediate crimped parts, said frame having studs in position to engage 25 said openings when said strap embraces said magnet, said crimped portions adapted to be pinched to secure said magnet firmly in position on said frame.
3. Means to secure a U-shaped magnet on 30 its frame comprising a flexible strap of non-magnetic material, said strap having end openings to engage studs on said frame and having crimped portions intermediate its ends adapted to be pinched to hold said magnet firmly in position.
4. A magnetic measuring instrument comprising a U-shaped magnet, a rotary indicating means between the poles of said magnet, a frame having a portion engaged by 40 and supporting said magnet, said frame having grooved studs adjacent the poles of the magnet, a strap of non-magnetic material surrounding the magnet and having openings to receive said studs, said strap having 45 angular crimped portions whereby, when the crimped portions are pinched together, the strap holds the magnet firmly in position.

In testimony whereof I affix my signature.
JOSEPH ZUBATY.
